The ornamental design for a bandage, as shown and described.

DESCRIPTION

FIG. 1 is a top view of a bandage of our design.

FIG. 2 is a first side view of the bandage of FIG. 1.

FIG. 3 is a second side view of the bandage of FIG. 1.

FIG. 4 is a third side view of the bandage of FIG. 1.

FIG. 5 is a fourth side view of the bandage of FIG. 1; and,

FIG. 6 is a bottom view of the bandage of FIG. 1. The broken lines shown in the figures are included for the purpose of illustrating portions of a bandage that form no part of the claimed design.
